WILLIAM C. HUEBNER, OF BUFFALO, NEW YORK, ASSIGNOR TO HUEBNER-BLEISTEIN
PATENTS COMPANY, OF BUFFALO, NEW YORK.

VACUUM PRESSURE DEVICE AND MASK.

Application filed February 5, 1923. Serial No. 616,938.

This invention relates more particularly to a vacuum pressure device, registering means and mask for contact photographic printing machines of that sort disclosed for example 5 in Patent No. 1,377,249, issued in my name, May 10, 1921, in which photographic prints are made on a photo-sensitive plate or surface from a transparent negative or printing plate held in contact with the sensitized 10 or print-receiving plate or surface. It is essential to perfect work in machines of this sort to provide means for insuring a perfect contact between the printing plate and the sensitized surface throughout the entire 15 area of the printing plate. Such machines are commonly used for photo-composing work which requires that the printing plate be positioned or registered with great precision with reference to the sensitized plate, 20 or with reference to a layout or copy, and often necessitates the repeating of prints from the same printing plate or from different printing plates, which may be of different sizes, in different required locations 25 and positions on the print-receiving surface. Where a succession of prints from the same or different printing plates are to be made in different locations on the same print-receiving surface, it is desirable when 30 making one print to mask or cover the remaining portions of the sensitized surface so as to prevent light action thereon. In photo-composing machines of the character mentioned, it is often desirable to photograph small images near the gripper and side edges of flexible sensitized metal press plates which are secured at their edges in a suitable holder in the machine, and it has been only in machines having special provision 35 for this purpose that it has been practicable to secure proper contact or pressure between the plates when printing small images near the edges or corners of the sensitized plate, on account of the necessity 40 for the holder for the printing plate to extend beyond the edge of the sensitized plate in order to so locate the prints.

One of the objects of this invention is to 50 provide a practical and desirable pressure device of simple and inexpensive construction for insuring a perfect contact of the printing plate and print-receiving surface throughout the whole surface area of the printing plate notwithstanding possible unevenness or variations in thickness in the

printing plate, and in which vacuum is utilized to cause the pressure of the contacting surfaces against each other; also to provide a device for this purpose which enables the printing plate to be positioned 60 or registered with precision in the required relation to the print-receiving surface, and enables the same or different printing plates to be accurately placed in different required locations or positions with reference to the 65 print-receiving surface; also to provide a device for causing the required contact between the printing plate and one portion of the print-receiving surface, and which forms a mask or light shield for the other 70 portions of the sensitized print-receiving surface; also to provide a device of the nature mentioned in which the printing plate is held in adjusted position on a printing plate holder or support so that the printing 75 plate can be accurately adjusted or registered with respect to its holder or support and whereby the printing plate holder with the printing plate secured thereon and the print-receiving plate can be readily moved 80 into and out of contact and adjusted relatively to each other without contact of the printing plate with the sensitized surface and consequent danger of injury to the 85 same; also to supply a simple device whereby various sizes of printing plates carrying images can be exposed near the edges as well as at other portions of the sensitized plate or surface, and proper contact between the plates assured, without the trouble usually attending the overlapping of large 90 printing plates bearing small images, or the need for an expensive assortment of special sized printing plate holders for printing plates of different sizes; and also to improve pressure and registering devices for photographic printing machines in the other respects hereinafter described and set forth 95 in the claims.

In the accompanying drawings: 100
Fig. 1 is a front elevation of a negative or printing plate holder and a vacuum pressure device or mask embodying my invention, showing a transparent printing plate in position thereon.

Fig. 2 is a sectional plan view thereof on line 2—2, Fig. 1.

Fig. 3 is a fragmentary similar view, showing the print-receiving plate held in printing contact with the printing plate. 110

Fig. 4 is a fragmentary section of a portion of vacuum mask of slightly modified construction.

Fig. 5 is a front elevation on a reduced scale, showing one method of securing the printing plate on the supporting glass of the plate holder.

Fig. 6 is a elevation on a reduced scale showing the printing plate holder and a vacuum mask for supporting a small printing plate so as to enable a print to be made at the edge or corner portions of the print-receiving plate or surface.

Fig. 7 is a perspective view of the vacuum mask detached.

Fig. 8 is a sectional view thereof on line 8—8, Fig. 1, showing the connection of the mask with the suction tube or pipe.

Fig. 9 is a section thereof on an enlarged scale on line 9—9, Fig. 8.

Fig. 10 is a fragmentary sectional perspective view showing one way of securing a printing plate on its transparent supporting plate.

Fig. 11 is a similar view showing another way of securing a printing plate on the supporting plate.

A represents a negative or transparent printing plate, and B a sensitized or print-receiving plate against the sensitized surface of which the printing plate is adapted to be pressed for making photographic prints on the print-receiving plate B by exposure to light passing through the transparent negative or printing plate. C is a back support, which may be a board or member of any suitable character adapted to bear against the back of the print-receiving plate to support or brace the same against deflection or movement when the printing plate is placed in contact with the print-receiving plate. The print-receiving plate B is ordinarily a thin metal plate provided with a light sensitive coating adapted, after being developed, to be used in a printing press for making ink impressions therefrom, and a photographic negative on a glass plate is ordinarily used as the printing plate A, and these parts are so shown in the drawings. In the machines in which my invention is ordinarily used for making photographic prints from the printing plate A on the print-receiving plate B, these plates are mounted facing each other in holders, one or the other, or both of which are movable for placing the printing plate opposite any required portion of the print-receiving plate and for placing the plates into and out of contact. The holder for the plate B is not shown, as this is not necessary to an understanding of the invention, but it should be understood that the holders can be arranged so as to support the plates vertically or in any other desired position.

The holder for the printing plate A pref-

erably consists of a suitable frame 15 provided with an opening 16 for the passage of light to the printing plate, and a transparent or glass supporting plate 17 which is mounted on the frame 15 over the light opening 16 therein and forms a support for the printing plate A. The supporting plate 17 is adjustably secured on the holder frame 15 so that the supporting plate 17 with the printing plate A thereon can be adjusted relatively to the holder frame 15 for the purpose of registering or accurately positioning the printing plate as may be required with reference to the print-receiving plate B, or with reference to a layout or copy. Any suitable adjusting and holding means for the supporting plate may be employed for this purpose. As shown, the supporting plate 17 is provided with bevelled edges and is adjustably held on one face of the holder frame 15 by holding fingers or members 18 which engage the edges of the plate and are adjustably connected by thumb screws 19 to the holder frame. The fingers are adapted to be moved for adjusting the supporting plate by appropriately adjusting the screws 19 so as to shift the supporting plate as required on the holder frame 15. As shown in Fig. 1, two of these holding fingers 18 are provided at each of the four edges of the supporting plate and are adapted to securely hold the plate in its adjusted position. The printing plate A is secured stationarily on the supporting plate and is adjusted on its holder as may be required by shifting the supporting plate 17 on the holder frame 15 by means of its adjusting screws 19. By loosening the fingers 18 at one or more edges of the supporting plate and tightening or advancing the remaining fingers, the supporting plate can be shifted in one or another direction and also angularly on the holder frame, so that by appropriate adjustments of the holding fingers the supporting plate can be shifted so as to place the printing plate in any desired position within the limits of adjustment of the holder as may be necessary to center or register the printing image or register marks on the printing plate in a predetermined or registered position with respect to the printing plate holder and to the printing machine in which the printing plate holder occupies a predetermined position, as presently explained. Thus the printing image on the printing plate can be registered with regard to a predetermined position on the printing machine, as well as with regard to the print-receiving plate B, as before mentioned. The printing plate can be secured on the face of the supporting plate 17 by any appropriate means, such for example as adhesive securing strips 20 placed along the edges of the printing plate with the strips adhering to the edges of the negative and to the support- 130

ing plate, as clearly shown in Fig. 10, or, if desired, the printing plate can be secured on the supporting plate by cement applied around the edges of the printing plate so as 5 to adhere to the latter and to the supporting plate, as represented at 21 in Fig. 11. Any other suitable way of securing the negative on the supporting plate could be employed.

The printing plate holder can be mounted 10 in the photographic printing machine or frame in any suitable way. Preferably this holder is removably secured in place in the machine on a support or frame 22 so that the printing plate holder with the printing plate mounted thereon can be quickly and 15 easily placed in predetermined position in the photographic printing machine after the printing plate has been properly secured and adjusted or registered on the holder 20 outside of the machine. For this purpose, as shown, the support 22 is provided with fixed studs 23 adapted to enter holes 24 in the back of the holder frame 15. The negative holder can thus be quickly placed in 25 and removed from the machine, and it will always occupy precisely the same predetermined position, and different holders having corresponding holes 24 can be similarly placed accurately in the same position on the support 22. Any other suitable means for 30 thus removably securing the printing plate holder in predetermined position in the machine could be employed, and if not desired, the printing plate holder need not be removable from the machine. In the photographic printing machine, light from a lamp or other suitable source of light passes through an opening 25 in the support 22 and the opening 16 of the frame 15 for illuminating the transparent printing plate, and usually the lamp is enclosed within a suitable housing or casing mounted on the support 22 so that the light from the lamp can escape only through the openings of the support 22 and plate holder, and cannot escape 40 around the plate holder and thus act on the sensitized plate except through the transparent supporting plate 17.

26 represents a mask or device for producing 50 the required close contact of the surface of the printing plate with the surface of the print-receiving plate, and for masking or covering the portions of the transparent supporting plate 17 which surround or project beyond the edges of the printing plate so as to prevent passage of light through such surrounding portions and the action of the light on the sensitized plate except through the printing plate. This 55 mask preferably consists of a flexible blanket or sheet of rubber or other suitable material impervious to light and air, which is removably secured on the printing plate holder overlying the supporting plate 17, 60 and is provided with an opening 26 through

which the printing plate is adapted to project. The mask is provided around this opening with a raised rib or portion 27 adapted to bear against the print-receiving plate so as to provide an annular vacuum 70 chamber 28 surrounding the printing plate from which the air is adapted to be exhausted for pressing the print-receiving plate against the printing plate. As shown, the mask blanket is provided at its corners 75 with perforated attaching tabs 29 adapted to be hooked over studs or hooks 30 on the corner portions of the plate holder frame 15, thus adapting the mask to be quickly secured in position simply by engaging the 80 tabs over the hooks or studs 30. Any other suitable means for removably securing the mask on the plate holder could be employed. The annular raised portion 27 of the mask projects outwardly from the face of the 85 mask slightly beyond the outer face of the printing plate and extends completely around the printing plate so that when this raised portion is pressed into contact with the print-receiving plate, a closed chamber 90 will be formed which is occupied by the printing plate. This chamber is connected by a passage 31 preferably in a raised portion 32 on the mask blanket extending from the chamber 28, to the edge of the mask 25, 95 the passage 31 being connected by a suitable coupling or connection 33 to a hose or pipe 34 which is adapted to be connected with a pump or device for exhausting air from the vacuum chamber 28. The annular raised 100 portion 27 and the raised portion 32 are preferably made of rubber or analogous yielding material adapted to be compressed by the pressure of the print-receiving plate thereon so as to insure an air tight joint 105 between the latter plate and the raised portion 27 of the mask or blanket. When therefore, the print-receiving plate is pressed against the raised portion of the mask or blanket and air is exhausted from the vacuum chamber, the air will be likewise exhausted from between the opposing surfaces of the printing plate and the print-receiving plate, so that the print-receiving plate will be pressed and held into firm, 110 close contact with the face of the printing plate. The pressure and contact will be uniform throughout the extent of the printing plate, irrespective of irregularities in its surface, because of the flexibility of the 115 print-receiving plate. In order to prevent the print-receiving plate, which is usually thin, from collapsing or being depressed into the exhaust passage 31, a raised rib 35 is 120 preferably provided on the blanket or mask 125 within the passage 31 so as to leave only narrow channels at opposite sides of this rib 35 which are so narrow that the print-receiving plate cannot be depressed therein sufficiently to prevent proper air tight joints 130

between the print-receiving plate and the outer walls of the exhausting passage.

If the print-receiving plate is too flexible to bear against the annular raised portion 27 of the mask with sufficient pressure to insure an air tight closure of the vacuum chamber, a suitable back support or pressure member, such as the member C illustrated in Fig. 3 can be employed to cause the necessary pressure of the print-receiving plate against the raised portion 27. In the case of a sufficiently stiff or rigid print-receiving plate or element, however, this back support or device C would not be essential.

15 If it is desired, the mask or blanket can be provided on its underside around the edge of its plate opening 26^a and opposite the portion 27, with a raised rib 36, as shown in Fig. 4, to bear against the glass supporting plate 17. This gives a restricted annular bearing part on the under or back side of the mask to engage the supporting plate to better assure an air tight joint between the mask and the supporting plate with less 25 pressure of the printing plate against the print-receiving plate.

The vacuum mask constructed as described could be molded or made in one integral piece, but it can be easily constructed by 30 cementing rubber or resilient strips on a flat sheet of rubber or analogous material to form the raised chamber and passage portions 28 and 31, so that masks suitable for different sizes of printing plates, or for small 35 printing plates located near the edge or corner of the plate holder can be readily made, and if necessary any skilled operator of a photo-composing machine can easily make a mask adapted for any particular requirement. Fig. 6 shows a mask with its 40 opening 26^a so arranged as to locate a small printing plate at one corner of the plate holder. This same mask can be used for locating the printing plate correspondingly 45 at any other corner of the plate holder, by simply turning and securing the mask in different positions on the plate holder. By means of the mask described, one printing plate holder of maximum size can be used 50 for any smaller size of negative or printing plate, and a practical degree of vacuum pressure of the printing plate against the print-receiving plate obtained, close to the image edge, by reason of the smaller size of 55 the printing plate which can be used for the image. At the same time the device serves as a light mask to prevent light action on the sensitized surface except only where intended, that is through the printing plate. 60 Since the printing plate is fixedly secured on the supporting plate 17 which is adjustably secured on the holder 15, the printing plate can be readily adjusted with precision to required position on the holder, and the 65 printing plate and print-receiving plate can

be placed into and out of contact and adjusted for making prints in different required positions on the print-receiving plate by adjustments of the holder for one or both of the plates in the manner usual in photographic contact printing machines, without disarranging the printing plate and without danger of injuring the sensitized surface. The printing plate and mask remain in place on the holder 15 and no readjustments thereof are necessary in making repeat prints.

I claim as my invention:

1. In a vacuum device for pressing a plate and an opposing element into contact face to face, the combination of a support on which said plate is secured and which is imperforate within the area thereof covered by said plate, a device which is removably mounted on said support, surrounds the periphery of said plate and bears against the face of said element and against said support uninterruptedly around the periphery of said plate to form a vacuum chamber in which said plate is located, and means for withdrawing air from said chamber.

2. In a vacuum device for pressing a printing element and a print-receiving element into contact, the combination of a support for the printing element which is imperforate within the area thereof covered by said printing element, a device which surrounds the periphery of the printing element between said support and said print-receiving element and bears against said support and against said print-receiving element and with said support and print-receiving element forms an air tight vacuum chamber in which the printing element is located, and means for withdrawing air from said chamber.

3. In a vacuum device for pressing a printing element and a print-receiving element into contact, the combination of a support for the printing element, adjustable means for stationarily securing said printing element in different adjusted positions on said support for registering the printing image with reference to said support, a device carried by said support and bearing against said print-receiving element and said support uninterruptedly around said printing element, said support, print-receiving element and device forming an air tight vacuum chamber in which the printing element is located, and means for withdrawing air from said chamber.

4. In a vacuum device for pressing a transparent printing element and a print-receiving element into contact, the combination of a transparent imperforate support against the face of which the printing element bears, a device which surrounds the periphery of the printing element and bears against said transparent support and against said print-

- receiving element uninterruptedly around said printing element to form a vacuum chamber between said print-receiving element and said support in which the printing element is located, and means for withdrawing air from said chamber.
5. In a vacuum device for pressing a transparent printing element and a print-receiving element into contact, the combination of a 10 transparent support for the printing element, a light mask which covers the portions of said transparent support surrounding the periphery of the printing element and is adapted to bear against the print-receiving element and said support and together with said print-receiving element and support to form a vacuum chamber in which the printing element is located, and means for withdrawing air from said chamber.
- 20 6. In a vacuum device for pressing a printing element and a print-receiving element into contact, the combination of a support on which the printing element is secured, a holder, means for adjusting said support 25 on said holder to adjust the printing element relatively to the holder, a device which surrounds the periphery of the printing element and bears against the print-receiving element and against said support, said support, print-receiving element and device being of a construction to form a vacuum chamber in which the printing element is located, and means for withdrawing air from said chamber.
- 30 7. In a vacuum device for pressing a transparent printing element and a print-receiving element into contact, the combination of a transparent supporting plate on which said printing element is secured facing 35 the print-receiving element, means for adjusting said supporting plate to adjust the printing element relatively to the print-receiving element, a light mask which surrounds the periphery of said printing element between the print-receiving element and said supporting plate and is adapted by contact with said print-receiving element and said supporting plate and together with said parts to form a vacuum chamber in which the printing element is located, and means for withdrawing air from said chamber.
- 40 8. The combination of a holder for a printing element which holder is provided with an adjustable supporting plate, means for securing a printing element on said supporting plate facing a print-receiving element, means for securing said supporting plate in different adjustments on said holder, a device which is adapted to bear against the print-receiving element and said support around the periphery of the printing element and together with said print-receiving element and said support to form a vacuum chamber in which the printing element is located, and means for withdrawing air from said chamber.
- 45 9. The combination of a holder for a printing element, which holder is provided with an adjustable supporting plate, means for securing a printing element on said supporting plate facing a print-receiving element, means for securing said supporting plate in different adjustments on said holder, a device which is carried by said plate holder and is adapted to bear against the print-receiving element and said supporting plate around the periphery of the printing element and together with said print-receiving element and said supporting plate, to form a vacuum chamber in which the printing element is located, and means for withdrawing air from said chamber.
- 50 10. The combination of a holder for a printing element, which holder is provided with an adjustable transparent supporting plate, means for securing a printing element on said supporting plate facing a print-receiving element, a light mask which is carried by said holder and surrounds the printing element between the supporting plate and the print-receiving element and is adapted to bear against said supporting plate and print-receiving element around the periphery of the printing plate and together with said supporting plate and print-receiving element to form a vacuum chamber in which the printing element is located, and means for withdrawing air from said chamber.
- 55 11. In a vacuum device for pressing a printing element and a print-receiving element into contact, the combination of a support for the printing element, a light mask comprising a flexible sheet placed between said support and the print-receiving element having an opening through which the printing element is exposed and an annular compressible raised portion which bears against the print-receiving element around the periphery of the printing element forming a vacuum chamber in which the printing element is located, and means for withdrawing air from said chamber.
- 60 12. In a vacuum device for pressing a printing element and a print-receiving element into contact, the combination of a support on which the printing element is secured, a flexible blanket carried by said support between the same and the print-receiving element, said blanket surrounding the printing element and bearing against the support and the print-receiving element to form a vacuum chamber in which the printing element is located, and means for withdrawing air from said chamber.
- 65 13. In a vacuum device for pressing a printing element and a print-receiving element into contact face to face, one of said elements being of larger area than the other,

a support for the smaller element adapted to project beyond the edge of said larger element, a mask which is disposed between said support and said larger element and 5 covers the projecting part of said support and is adapted to bear against the surface of said larger element around the edges of said smaller element and together with said print-receiving element and support to form 10 a closed vacuum chamber in which the smaller element is enclosed, and means for exhausting air from said vacuum chamber.

14. In a vacuum device for pressing a printing element and a print receiving element into contact, the combination of a support for the printing element, means for stationarily securing said printing element in different adjustments on said support for registering the printing image with respect to said support, a device which is arranged between and is adapted to bear against said support and said print-receiving element around the periphery of said printing element and together with said support 20 and print-receiving element to form a vacuum chamber in which the printing element is located, and means for withdrawing air from said vacuum chamber.

15. The combination of a print-receiving element, a holder for a printing element

constructed to occupy a predetermined position in a printing machine, means for stationarily securing said printing element in different adjusted positions on said holder, a device arranged and constructed to bear 35 against the face of said print-receiving element around said printing element and in cooperation therewith to form an air tight vacuum chamber in which the printing element is located, and means for withdrawing 40 air from said vacuum chamber for pressing said printing element and print-receiving element into contact face to face.

16. In a vacuum device for pressing a printing element and an opposing element 45 into uniform close contact, the combination of a transparent support on the face of which said printing element is supported facing said opposing element, said support being imperforate in the area thereof covered 50 by said printing element, a device which is adapted to contact with said support and said opposing element and form an air tight 55 closure around the periphery of said printing element for the space between said support and said opposing element within which said printing element is located, and means for withdrawing air from the space closed by said device.

WILLIAM C. HUEBNER.
